UNITED STATES PATENT OFFICE.

LILLIAN M. LEA, OF TOTTENVILLE, NEW YORK.

SHAMPOO CUP.

Application filed May 29, 1922. Serial No. 564,494.

To all whom it may concern:

Be it known that I, LILLIAN M. LEA, a citizen of the United States, and a resident of Tottenville, borough of Richmond, in the county of Richmond and State of New York, have invented a new and Improved Shampoo Cup, of which the following is a full, clear, and exact description.

This invention has relation to a shampoo cup which is particularly designed as a combined receptacle and applicator for a shampoo liquid.

As an object the invention contemplates a simple and effective device for holding a supply of shampoo fluid and for affording means to facilitate the application and distribution of the fluid on and over the head to expedite the shampooing operation.

As a further object the invention contemplates a device which affords a convenient means for mixing the constituent elements of the shampooing agent prior to its application to the head.

As a still further object the invention aims to provide as an inexpensive article of manufacture a shampoo cup which is highly efficient in its purpose and strong and durable in its construction.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

40 In the drawings—

Figure 1 is a view illustrating a shampoo cup constructed in accordance with the invention and the manner in which the same is used.

45 Fig. 2 is a sectional view through the cup. Fig. 3 is a plan view thereof.

Referring to the drawings by characters of reference, the cup comprises a body 10 which is provided with a closed bottom 11 and an open upper end 12 which is defined by an inwardly and downwardly directed or curved flange 13. The side wall is bent or

offset inwardly as at 14 between the bottom and lower compartments 15 and 16 which are connected by a restricted passage or 55 throat 17. The lower portion of the body is of an external configuration and size to conveniently fit within the palm of the hand when in use.

In use and operation, the constituent elements constituting the shampoo fluid 18 is placed in the cup. By using one of the hands as a cover and grasping the lower portion of the same in the other hand, the cup is employed as a mixer for shaking and thoroughly mixing the constituent elements of the shampoo agent. When the shampooing agent is properly mixed the lower portion of the cup is used as a handle for manipulating the same and the upper open end 12 is 70 brought into contact with the scalp and moved over the same to effect the discharge, application and distribution of the contents over the head. The inwardly and downwardly directed or curved flange 13 provides a depression or concave extremity which closely conforms to the various contours of the scalp to prevent overfeeding of the contents and resultant waste or loss thereof. When not in use the cup may be 75 thoroughly cleansed and sterilized until again needed. The cup may be constructed from glass, porcelain, metal or any other suitable material and is so formed as to eliminate sharp edges or corners which might tend to cut or injure the hair. In initially bringing the cup into applied position with the scalp, the same is preferably turned sideways with the open upper end 12 against the side of the head to prevent the spilling 80 and waste.

I claim:

1. A shampoo cup comprising a body having an open end and a closed end, an annular inwardly projecting portion between said ends for separating said body into individual compartments connected by a restricted passage, and an inwardly curved flange at the upper open end providing a depressed extremity adapted to closely fit the contour of the head to insure an even discharge and application of the contents upon the head. 95

2. A shampoo cup comprising a body having an open end and a closed end, an annu-

lar inwardly projecting portion between said ends for separating said body into individual compartments connected by a restricted passage, and an inwardly curved flange at the upper open end providing a depressed extremity adapted to closely fit the contour of the head to insure an even dis-

charge and application of the contents upon the head, the exterior configuration of the compartment adjacent the closed end serving to closely fit the palm of the hand to afford convenient means for manipulating the cup during the applying operation.

LILLIAN M. LEA.
